GOVERNOR APPARATUS

Walter Schmid, Philadelphia, Pa., assignor to Westinghouse Electric & Manufacturing Company, East Pittsburgh, Pa., a corporation of Pennsylvania

Application July 27, 1940, Serial No. 347,908

2 Claims. (Cl. 74—3)

My invention relates to an emergency or overspeed governor and it has for an object to provide apparatus of this character which is sparkless in operation and therefore safer in inflammatory or explosive media environments.

The usual overspeed governor includes a metallic weight or pin movable diametrically of the rotating shaft of the prime mover or turbine upon overspeeding to strike and trip a lever to close the throttle valve. Usually the lever is made of metal and impact of the pin therewith involves metal-to-metal contact. While this arrangement is ordinarily satisfactory, yet, where the prime mover is rotated in an enclosure likely to have highly inflammatory or explosive media, as is the case with certain oil refineries, the hazard of fire or explosion is encountered on account of sparking due to the metal-to-metal contact of the pin with the lever. While attempts have been made to alleviate this difficulty by making the trip lever of spark-resisting metal, for example, brass or other special metals, nevertheless, not only will these metals spark under certain conditions, but they are so soft that frequent replacement is required. Also, attempts have been made to meet the inflammatory and explosive condition by having the prime mover enclosed in a conduit communicating with space external to the inflammatory and explosion zone.

I have found that the foregoing objections may be overcome by making at least the contact portion of the trip lever of suitable hard and wear-resisting non-metallic material to avoid metal-to-metal contact and consequent sparking. The material may comprise, for example, linen or canvas impregnated with a suitable amorphous or resinous substance such as a phenolic condensation product. Such a material, not only has the advantage of avoiding metal-to-metal contact and the consequent danger of sparking with the possibility of explosion, thereby making it possible to install fluid-operated prime movers in situations heretofore regarded as too hazardous, but installation may be effected without the cumbersome and expensive equipment to make it explosion-proof and the material has the advantage of enduring blows of the trip pin more satisfactorily than the usual metal lever and with reduced wear.

It is, therefore, an object of the invention to provide an overspeed or emergency governor in which the trip lever has at least the portion thereof for contact by the tripping pin made of canvas or linen impregnated with resinous ma-

terial so as to avoid metal-to-metal contact and consequent sparking.

These and other objects are effected by the invention as will be apparent from the following description and claims taken in connection with the accompanying drawing, forming a part of this application, in which:

Fig. 1 is a partial sectional view showing an overspeed trip mechanism with my improved structure;

Fig. 2 is an enlarged partial sectional view showing the trip lever; and,

Fig. 3 is a sectional view taken along the line III—III of Fig. 2.

Referring now to the drawing more in detail, I show an overspeed governing mechanism 10, mounted in a casing 11, in which rotates a turbine shaft 12. A weight or trip pin 13 is carried in an opening 14 extending diametrically of the shaft 12. The weight has its center of gravity slightly offset from the axis of rotation and normally, it is held in place by a compression spring 15 and a retainer 16. When the weight flies out, it trips the arm 17 of the multiple arm lever 18 to release mechanism, at 19, to permit the spring 20 to close the throttle valve 21.

As heretofore pointed out, at least that portion of the lever arm 17 contacted by the pin 13 is made of suitable hard, wear-resisting, non-sparking, amorphous material. For this purpose, I prefer to use fabric, such as linen or canvas, impregnated with a resin such as a phenolic condensation product; and this composite structure is preferably embodied as an insert or facing 22 for the lever arm 17 and positioned for contact by the pin.

While the insert or facing may be attached to the lever arm 17 in any suitable manner, I preferably provide the latter with a recess 23 open at 40 the sides and having dovetail ends 24. The insert is formed with dovetail ends 25 to fit the recess ends 24; and, with the insert positioned in the recess, it is retained by lap plates 26 detachably secured to the sides of the lever arm.

While the invention has been shown in but one form, it will be obvious to those skilled in the art that it is not so limited, but is susceptible of various changes and modifications without departing from the spirit thereof, and it is desired, therefore, that only such limitations shall be placed thereupon as are specifically set forth in the appended claims.

What is claimed is:

1. In apparatus for use in inflammatory or explosive environments, a shaft rotatable nor-

mally at a relatively high speed, trip mechanism including a lever disposed adjacent to the shaft and movable outwardly therefrom an amount required to release the mechanism and a pin carried by the shaft so as to be normally free of the lever but which, under the influence of centrifugal force, is movable radially outward with respect to the shaft when the latter overspeeds to a predetermined extent to engage the lever and then, with continued outward radial movement, to engage the lever repeatedly to move the latter the amount required to release the trip mechanism, said lever including at least the pin-contact portion thereof comprised by a hard, tough, wear-resisting and nonsparking material including fabric impregnated with a suitable synthetic resin.

2. In apparatus for use in inflammatory or

explosive environments, a shaft rotatable normally at a relatively high speed, trip mechanism including a lever disposed adjacent to the shaft and movable outwardly therefrom to release the mechanism and a pin carried by the shaft so as to be normally free of the lever but which, under the influence of its centrifugal force, is movable radially outward with respect to the shaft when the latter overspeeds to a predetermined extent to engage the lever and then, with continued outward radial movement, to engage the lever repeatedly to move the latter the amount required to release the trip mechanism, said lever having a pin-contact facing comprised by a hard, tough, wear-resisting and non-sparking material including fabric impregnated with a suitable synthetic resin.
